W. D. PIERSON

DIE HOLDER

Filed April 21, 1921

Inventor
William D. Pierson
By George E. Tracy
Atty

UNITED STATES PATENT OFFICE.

WILLIAM D. PIERSON, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

DIE HOLDER.

Application filed April 21, 1921. Serial No. 463,168.

To all whom it may concern:

Be it known that I, WILLIAM D. PIERSON, a citizen of the United States, residing at Waterbury, in the county of New Haven 5 and State of Connecticut, have invented certain new and useful Improvements in Die Holders, of which the following is a specification, reference being had therein to the accompanying drawings.

10 This invention relates to die holders and it is the principal object of the invention to provide a simple and effective device for readily removing the die from the lubricant in a wire drawing machine.

15 The improvements in the details of construction and arrangements of parts will be apparent from an inspection of the accompanying drawings in connection with the description hereinafter contained and 20 wherein a preferred embodiment of the invention is disclosed for the purpose of imparting a full understanding of the same.

In the drawings,—

25 Figure 1 is a fragmentary plan view of a wire drawing machine; and

Figure 2 is an enlarged perspective view of my improved die holder shown in connection with parts of the wire drawing machine immediately associated therewith.

30 This invention is particularly adapted for use with wire drawing machinery, wherein the dies are submerged in a lubricant. This lubricant becomes heated during the operation of the machine to such a degree that 35 it is impossible to place the hand therein. The lubricant at times also becomes dangerous to an operator, because the passage of copper and brass or similar wire therethrough contaminates it, and septic conditions thus result that make the process of 40 removing a die from the lubricant by the hand one to be avoided if possible.

45 Heretofore it has been the practice to locate the die in the lubricant by placing the hand therein or by a blind search first with a wire or similar device and then remove it. This is objectionable, not only for the above reasons but because the die is

frequently found at a point distant from where it is expected to be located and when 50 found it is usually difficult to get a sufficient hold thereon to lift it from the lubricant. This difficulty is accentuated by the fact that the die is usually cylindrical in shape or 55 in the form of a frustum of a cone. These, and other objections, I have eliminated with my improved die holder, whereby the die as soon as it is released drops into a holder, the movement of which raises the die out 60 of the lubricant without requiring a search therefor or the necessity of the operator placing his hands in the lubricant itself.

Having more particular reference to the drawings, wherein like figures of reference designate like parts in both figures, the 65 numeral 10 designates the bed of the wire drawing machine, 11 two wire drawing drums, 12 the die which is held against the fixed die head 14 by the wire 13 being drawn therethrough, having a slot 15 in 70 the top edge thereof. The bed 10 having walls 16 upon opposite sides thereof contains the lubricant up to about the top of the die head 14 and the wire 13 is drawn through the die by the rotation of the 75 drums 11.

The mechanism above described is all old in the art and constitutes no part of my present invention.

My improved die holder comprises a box 80 or container 17 which is open on one side and provided with a slot 18 in the opposite side which in its down position is opposite the slot 15 in the die head 14. Lugs 19 are provided on the box or container and 85 through which project the pins or guides 20 fixed in the bed 10, whereby said box or container is movably mounted in relation to said die head. A lifter 21 provides a convenient means for manually moving said 90 box. It is, of course, possible to make this box or container 17 of any other shape or material, even of wire mesh, if so desired.

When the end of the wire 13 has passed through the die 12 and pressure thereon is 95 released, said die 12 drops into the box or

5 container 17 and is then readily removed from the lubricant either for threading another wire therethrough or for any other purpose, by merely lifting said box or container upwardly by means of the lifter 21 and thus raise said die 12 from its submerged position.

10 While I have shown the die holder as being mounted upon the pins or guides 20 connected with the bed 10, it is obvious that it may be slidably connected with the die head 14 and operate equally as well, so therefore desire it to be understood that the mounting means herein shown and described 15 are only one of the many means that may be utilized for accomplishing this purpose.

20 Minor changes and alterations may be made within my invention, aside from those herein suggested, and I would therefore have it understood that I do not limit myself to the exact construction herein shown and described, but claim all that falls fairly within the spirit and scope of the appended 25 claims.

25 5. What I claim as new and desire to secure by Letters Patent, is:—

30 1. A device for the purpose described, comprising a box or container separate and independent from the die, and in which the die is held, with means for movably mounting the same upon a wire drawing machine adjacent to the die head.

35 2. In combination with the die head of a wire drawing machine; a box or container separate and independent from the die, and in which the die is held, having one open side; and means for movably mounting the same adjacent to said die head.

40 3. In combination with the die head of a wire drawing machine; a box or container movably mounted adjacent thereto and having one slotted side, which slot in one of its positions is opposite to the slot in said die head.

45 4. In a device of the character described, the combination with the die head; of a box; means for movably mounting the same in relation thereto, said box having one open side and a slot through the opposite side, which slot in one of its positions is opposite the slot in said die head.

50 5. In a wire drawing machine, the combination with a die head; of guiding means connected therewith adjacent to said die head; and a box movably mounted upon said guiding means, said box having an open face adjacent to said die head and a slot in the opposite face.

55 6. In combination with the die head of a wire drawing machine; a box or container movably mounted adjacent thereto with one open side that is closed by said die head and having a slot in the opposite side that opens through the top of the box.

7. In combination with the die head of a 65 wire drawing machine; guide means secured adjacent thereto and substantially parallel with one face thereof; and a box or container slidably mounted upon said guide means.

8. In combination with the die head of a wire drawing machine; a plurality of guides fixed relatively to said die head; a box or container movably mounted upon said guide means and having one open side which is 75 closed by said die head.

9. A device for the purpose described, comprising a box or container separate and independent from the die head, with means for movably mounting the same upon a wire 80 drawing machine adjacent to the die head; and means projecting upwardly above said box or container for lifting the same.

10. In a device of the character described, a bed shaped so as to hold a liquid; a die 85 head fixed in said bed so as to be either wholly or in part within said liquid; a box or container having one open side movably mounted relatively to said bed within said liquid, and having an opening in one side 90 thereof which in one of its positions, is opposite the opening in said die head; and means connected with said box or container connected therewith and exposed above the surface of said liquid for moving the same 95 relatively to said die head.

11. A device for the purpose described, comprising a box or container separate and independent from the die, shaped so as to hold the die loosely therein, with means for 100 movably mounting the same upon a wire drawing machine adjacent to the die head.

12. A device for the purpose described, comprising a box or container separate and independent from the die, shaped so as to 105 hold the die loosely therein, with means for movably mounting the same upon a wire drawing machine adjacent to the die head and carrying with it the said die.

13. A device for the purpose described, comprising a box or container so shaped that the die may rest upon a portion thereof and partially surrounded by another portion; and means for movably mounting the same upon a wire drawing machine adjacent to the die head.

14. A device for the purpose described, comprising a box or container, having a solid bottom and an open top and of sufficient size to permit a die to be placed therein and rest upon said bottom; and means for movably mounting the same upon a wire drawing machine adjacent to the die head.

15. A device for the purpose described, comprising a box or container, having a bottom portion, side portions, and an open top, and of sufficient size to hold a die

therein; and means for movably mounting the same upon a wire drawing machine adjacent to the die head.

16. A device for the purpose described, comprising a box or container separate and independent from the die and of sufficient size as to permit said die to move freely therein, and means for movably mounting

said box or container upon a wire drawing machine adjacent to the die head so that 10 said die will contact upon one side with said die head.

In testimony whereof, I have hereunto affixed my signature.

WILLIAM D. PIERSON.
